UNITED STATES PATENT OFFICE.

JAMES BLOODGOOD, OF BRIGHTWOOD, AND JOHN G. O'DONNELL, OF LEON,
VIRGINIA.

GRUBBING-MACHINE.

SPECIFICATION forming part of Letters Patent No. 638,169, dated November 28, 1899.

Application filed June 17, 1899. Serial No. 720,961. (No model.)

To all whom it may concern:

Be it known that we, JAMES BLOODGOOD, of Brightwood, and JOHN G. O'DONNELL, of Leon, in the county of Madison and State of 5 Virginia, have invented a new and useful Improvement in Grubbing-Machines or Sprout-Pullers, of which the following is a specification.

This invention is a new and useful construction of grubbing-machine or puller, the object being to provide an exceedingly cheap and simple device which can be readily carried about and operated by one person.

Another object of the invention is to provide a device consisting of exceedingly few parts, all of which are thoroughly braced, so that all danger of breakage during operation is avoided.

Another object of the invention is to provide a device of the kind described which will be certain in its action, avoiding slipping, which has been one of the principal defects in all grubbing-machines or sprout-pullers heretofore used.

With these objects in view the invention consists, essentially, of a lever pivotally mounted on a bracket, said bracket having a forwardly-projecting arm having a hook at its forward end adapted to act in conjunction 25 with the forward end of the lever, a supporting-bracket, arm, and lever, all being braced to prevent strain and breakage.

The invention consists also in constructing the supporting-bracket, arm, and hook from 35 a single piece and also in the peculiar manner of bracing or strengthening the said arm.

The invention consists also in certain details of construction and novelties of combination, all of which will be fully described 40 hereinafter, and pointed out in the claims.

In the drawings forming part of this specification, Figure 1 is a perspective view showing the bracket portion of our invention. Fig. 2 is a detail perspective view of the supporting-bracket, the lever being removed; and Figs. 3, 4, and 5 are perspective views of slightly-modified forms of machines, all constructed in accordance with the broad principle of our invention.

In carrying out the invention we employ a base-block A, which may be of any suitable

size and form and to which is rigidly attached a supporting-bracket B, said supporting-bracket comprising a flat horizontal member B', which is rigidly attached to the base-block, and the side members B² carried up essentially parallel and provided with perforations through which the pivotal bolt C passes, said bolt serving to connect the lever D to the supporting-bracket. The forward end of 60 the lever is sheathed by means of a metallic strap D', and in order to employ a light construction of lever and at the same time provide a very strong one we employ a metallic truss-rod D², which is fastened by means of 65 a bolt D³ passing through the forward end and by means of a ring D⁴ passing through an eye D⁵, formed upon the upper end of the truss-rod, said ring being locked into a notch D⁶, produced beneath the under edge of the lever 70 D. A suitable bridge D⁷ is interposed between the lever and truss-rod intermediate of its ends, thereby providing an exceedingly light and strong lever. A forwardly-projecting arm E is formed integral with one. 75 of the side members of the supporting-bracket and at its forward end is provided with a hook F. This hook is reinforced by turning the metal back upon itself and carrying same back to a point beyond the pivotal bolt, said 80 pivotal bolt serving to secure the return end of the arm, thereby producing an arm of double strength, and by curving the said return portion slightly downward we provide a truss for the arm, and inasmuch as the outer portion thereof must necessarily be strained before the inner portion could be broken, by providing the double hook and arm we reinforce 85 or strengthen that portion of the machine which is subjected to the greatest strain. We 90 also provide a brace-rod G, which is secured at its lower end to the base-block or supporting-bracket and at its upper end to the forwardly-projecting arm adjacent to the forward end, thereby holding the said arm in its 95 proper position with relation to the supporting-bracket. The lever being pivoted adjacent to its forward end in the supporting-bracket is adapted to be brought into contact with the root or sapling to be pulled, while 100 the hook of the arm is brought into contact with the other side of the root or sapling at a

point above the point of contact of the lever, and by rocking the supporting-bracket upon the base-block the root or sapling can be quickly and easily uplifted, and the machine 5 is then ready for operation again.

By constructing the supporting-bracket and lever in the manner described we are enabled to provide an exceedingly strong and at the same time a very light machine, so that it can 10 be quickly and easily carried from place to place as desired.

In Fig. 3 we have shown a very slight modification, in which the forward end of the arm is bent horizontally to provide a jaw instead 15 of a hook, and the end is then returned to provide a reinforcement, and the same bolt which secures the upper end of the brace-rod also secures the return end of the jaw.

In Fig. 4 we have shown the supporting-bracket as composed of two pieces, and in Fig. 20 5 the supporting-bracket is of substantially the same construction, and the forward end of the arm is bent transversely across and the lever is provided with a metallic strap which 25 is bent substantially parallel to the end of the arm. In all of these modifications the principle of our invention is exactly the same, inasmuch as the brace-rod is employed in each one, and, furthermore, the forwardly-projecting 30 arm and the transverse jaw or hook are also employed.

It will thus be seen that our invention is capable of carrying out all of the objects herefore mentioned.

35 Having thus fully described our invention, what we claim as new, and desire to secure by Letters Patent of the United States, is—

1. In a grubbing-machine, a supporting-bracket having a forwardly-projecting arm 40 provided with a hook at its forward end, a lever pivoted in the supporting-bracket, and a brace-rod extending from the base of the supporting-bracket into the forward end of the

forwardly-projecting arm, substantially as shown and described. 45

2. In a grubbing-machine, a supporting-bracket comprising the base and side members, a forwardly-projecting arm formed from a single piece of metal, the hook upon the forward end of said arm, and the return portion, substantially as shown and described. 50

3. In a grubbing-machine, a supporting-bracket, comprising the base and side members, a forwardly-projecting arm formed from a single piece of metal, the hook upon the 55 forward end of said arm, a return portion, and the brace-bar extending from the base of the supporting-bracket to the forward end of the forwardly-projecting arm, substantially as shown and described. 60

4. In a grubbing-machine, a brace-block having a supporting-bracket attached thereto, said supporting-bracket comprising a base portion and side members, the forwardly-projecting arm integral with one of the side members, the hook at the forward end of said arm, the return portion connected as described, and the lever pivotally connected to the supporting-bracket, substantially as shown and described. 70

5. In a grubbing-machine, a brace-block having a supporting-bracket attached thereto, said supporting-bracket comprising a base portion and side members, the forwardly-projecting arm integral with one of the side members, the hook at the forward end of the said arm, the return portion connected as described, and the lever pivotally connected to the supporting-bracket, a brace-rod secured upon the upper face of the lever, substantially as shown and described. 75 80
